(57) **CLAIM**

The ornamental design for a food container, as shown and described.

DESCRIPTION

FIG. 1 is a top, front perspective view of a first embodiment of a food container showing our new design;

FIG. 2 is a bottom, front perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof;

FIG. 9 is a top, front perspective view of a second embodiment of a food container showing our new design;

FIG. 10 is a bottom, front perspective view of the food container of FIG. 9;

FIG. 11 is a front elevation view of the food container of FIG. 9;

FIG. 12 is a rear elevation view of the food container of FIG. 9;

FIG. 13 is a right elevation view of the food container of FIG. 9;

FIG. 14 is a left elevation view of the food container of FIG. 9;

FIG. 15 is a top plan view of the food container of FIG. 9; and,

FIG. 16 is a bottom plan view of the food container of FIG. 9.

The broken lines shown illustrate portions of the food container and form no part of the claimed design.

1 Claim, 16 Drawing Sheets
